UNITED STATES PATENT OFFICE.

SAMUEL T. BATES AND THOMAS C. ALLISON, OF HOHENWALD, TENNESSEE.

BOMB.

1,279,224.

Specification of Letters Patent. Patented Sept. 17, 1918.

Application filed March 29, 1918. Serial No. 225,499.

To all whom it may concern:

Be it known that we, SAMUEL T. BATES and THOMAS C. ALLISON, citizens of the United States, residing at Hohenwald, in 5 the county of Lewis, State of Tennessee, have invented a new and useful Bomb, of which the following is a specification.

The subject of this invention is a bomb, and the main object of the invention is the provision of a main body having cartridge or shell chambers arranged thereon, and chambered out to receive a firing plunger which is adapted to receive explosive for the purpose of bursting the bomb after the manner of an explosive shell.

Another object within the contemplation of the invention is the provision of means for firing the cartridges in advance of the charge of explosive.

The invention also contemplates generally improving the construction and enhancing the utility of devices of this character.

With the foregoing and other objects in view which will appear as the description proceeds, the invention resides in the combination and arrangement of parts and in the details of construction hereinafter described and claimed, it being understood that changes in the precise embodiment of the 30 invention herein disclosed can be made within the scope of what is claimed without departing from the spirit of the invention.

A practical embodiment of the invention is shown in the accompanying drawings, 35 wherein:

Figure 1 is a view in longitudinal section of a bomb constructed in accordance with the invention;

Fig. 2 is a cross section on the line 2—2 of

Fig. 1;

Fig. 3 is a view in elevation, partly in section, showing the device in fired position;

Fig. 4 is a fragmentary view in perspective of the plunger.

Referring to the drawings by numerals of reference:

In carrying out the invention there is provided a hollow body 10, preferably of cylindrical formation, and headed at one end, the 50 headed end being provided with a nipple 11.

The wall of the body 10 is tapped at various points to receive the threaded ends of tubes or barrels 12 which are provided to receive cartridges 13. The inner face of the wall of 55 the body 10 converges toward the headed

end of the body, thus providing a frusto-conical chamber or bore in the body.

Within the body 10 is mounted a frusto-conical shell or tube 14 which is provided with a series of apertures for the reception of firing pins 15, which are so positioned as to contact the caps of the cartridges 13 when the device is assembled and loaded. The opened end of the body 10 is formed with an outstanding annular flange which is apertured to receive bolts or the like for the purpose of securing a closure plate or head 16 in place on this end of the body.

The head 16 is formed with an apertured boss 17, through which and the nipple 11 a plunger rod 18 extends and in which it is 70 slideable. The plunger rod 18 has mounted thereon, within the body 10, a frusto-conical firing member 19, which is hollow and formed with a central cylindrical member 19' which encircles the rod 18. The firing member may be secured to the rod 18 in any preferred manner, but, as herein shown, the member and rod are provided with alining 75 apertures or bores for the reception of a pin 20 which serves to lock the parts firmly together. The base or lower end of the firing member 19 is closed in any suitable manner as by the annular screw plate 21, and within the member may be placed explosive 80 22. The closure plate 21 is provided with a flash hole in which is secured a cap 23 which may be discharged to ignite the explosive 22.

The boss 17 of the head 16 is apertured 90 to receive a firing pin 24, which is slideable through the aperture and in position to strike the cap 23, and the pin is normally held in extended position and away from contact with the cap by a compression spring 95 25 which encircles the stem of the pin and one end of which abuts the boss 17 of the head 16, while the other end contacts a pin or collar secured to the stem of the pin 24.

The plunger rod 18, at that portion extending beyond the boss 17, is encircled by 100 a collar 26, which is integral with or rigidly secured to the rod, and mounted to slide on the end of the rod is a cap 27 formed with an outwardly extending annular flange 27' at its upper or inner end. The cap 27 is 105 apertured to receive a pin 28 which passes through a slot 29, which slot is formed diametrically of the rod 18 and extends for a short distance longitudinally thereof adjacent its end. The pin 28 has a sliding fit 110

in the slot 29 so that the cap may slide upon the rod. The cap 27 is held in its extended or normal position by means of a compression spring 30 which encircles the rod 18 and is confined between the collar 26 and the inner end of the cap 27.

A tubular member 31 is threaded or otherwise secured on the nipple 11 and this member is formed with radially extending wings 10 or vanes 32. The plunger rod 18 passes through the tubular member 31 and terminates in a ring 33 by which the bomb may be hung for dropping from an air ship or the like.

15 In order that the plunger rod may be held in normally extended position, bores 34 are formed in the boss 17 and rod 18, of which they extend diametrically, and these bores align when the rod 18 is in extended position for the purpose of receiving a sheer pin by which the rod 18 is normally held. This sheer pin is of such strength that it will shear before the spring 30 compresses and allow the plunger rod 18 to be driven 20 inwardly upon impact of the cap 27 with the earth or other resisting object.

When the plunger rod 18, having been forced inwardly, becomes anchored by the firing member 19 coming in contact with the firing pins 15 and the casing 14, the spring 30 will compress and allow the cap 27 to slide upon the rod 18 until the flange 27' contacts the end of the stem of the firing pin 24 and forces the pin against the cap 23 25 to explode the charge in the member 19.

From the foregoing it will be evident that the sheer pin acts to hold the parts of the bomb in such position as to prevent accidental explosion, and that, when the bomb 40 is dropped, the wings or vanes 32 will tend to maintain it in proper, upright position so that the cap 27 will first contact the object upon which the bomb falls. When the bomb strikes, the cartridges or shells 13 will first 45 be fired and then the bomb exploded, as heretofore explained.

Having thus described the invention, what is claimed as new and sought by Letters Patent, is:—

50 1. A bomb, including a tubular body having a series of apertures, tubes threaded in the apertures and adapted for the reception

of shells, a lining within the tubular body, firing pins slideable in the lining and positioned to contact the caps of the shells, a 55 plunger rod extending through the body and arranged longitudinally thereof, a frusto-conical firing member secured to the rod and adapted to contact the firing pins, and means for exploding the bomb after 60 the firing member has contacted the firing pins.

2. A bomb, including a tubular body having a series of apertures, tubes threaded in the apertures and adapted to receive shells, 65 firing pins slideable within the body and positioned to contact the shells, a plunger rod slideable through the body, a hollow frusto-conical firing member secured to the rod for contacting the firing pins, the said 70 firing member charged with explosive, means for normally retaining the firing member in non-firing position, and means for igniting the charge in the firing member after the member has contacted the firing 75 pins to discharge the shells.

3. A bomb, including a tubular member having a series of apertures, tubes threaded in the apertures and adapted for the reception of shells, firing pins slideable in the 80 tubular member and positioned to contact the shells, a plunger rod slideable through the tubular member, a frusto-conical firing member secured to the rod and adapted to contact the firing pins, the said firing member charged with explosive, means engaging 85 the rod for normally retaining the firing member out of contact with the firing pins, a firing pin for exploding the charge in the firing member, and means carried by the 90 rod for actuating the last mentioned firing pin whereby the charge in the firing member will be exploded after the firing member has contacted the first mentioned firing pins and discharged the shells.

In testimony that we claim the foregoing as our own, we have hereto affixed our signatures in the presence of two witnesses.

SAMUEL T. BATES,
THOMAS C. ALLISON.
